UNITED STATES PATENT OFFICE

PAUL G. ANDRES, OF LA GRANGE, ILLINOIS, ASSIGNOR TO TEMPLE CORPORATION, OF CHICAGO, ILLINOIS, A CORPORATION OF DELAWARE

LOUD SPEAKER

Application filed May 27, 1929. Serial No. 366,421.

My invention relates to loud speakers, and has among its other objects the production of devices of the kind described that are efficient, durable and simple in construction.

5 A particular object of the invention is to provide improved means for bringing the reproducing unit or mechanism of a loud speaker into adjusted positions with respect to the diaphragm.

10 Another particular object of the invention is to provide improved means for operatively connecting the diaphragm of a loud speaker to the reproducing unit thereof.

The preferred form of the invention is 15 embodied in a loud speaker comprising a plurality of tensioned diaphragms which have their central portions operatively connected to a reproducing unit, the reproducing unit being provided with an armature disposed 20 within a coil subjected to telephonic currents. Improved adjustable means is provided for connecting the diaphragm to the armature and the reproducing unit is mounted on a bracket which may be brought into adjusted 25 positions with respect to the diaphragm to properly position the armature within the coil.

Many other objects and advantages will 30 become apparent as this description progresses, reference being had to the accompanying drawings, wherein:

Figure 1 is a rear elevation of a loud speaker embodying the invention;

Fig. 2 is a section taken on line 2—2 of 35 Fig. 1;

Fig. 3 is a section taken on line 3—3 of Fig. 1;

Fig. 4 is a section taken on line 4—4 of 40 Fig. 1;

Fig. 5 is a section taken on the line 5—5 of Fig. 1, and

Fig. 6 is a section taken on line 6—6 of Fig. 4.

In the drawings, I have illustrated my 45 invention as embodied in a loud speaker comprising a plurality of diaphragms, but it is to be understood that my invention is limited to this construction only to the extent indicated in the appended claim.

50 The loud speaker illustrated in the draw-

ings preferably comprises a rectangular frame 10 provided with a pair of spaced cross-bars 11 to which a pair of spaced vertical bars 12 are rigidly secured. The diaphragm 14 is preferably formed from fabric, 55 or the equivalent, and has its marginal portions rigidly secured to the frame 10 and a smaller diaphragm 15 of like material has its marginal portions secured to the cross-bars 11 and the vertical bars 12. It will be noted 60 that the diaphragms 14 and 15 are tensioned along divergent lines and that they are somewhat conical in shape to provide apices which are apertured to receive a sleeve or bushing 17 (see Fig. 5). The apertured portions or apices of the diaphragms 14 and 15 are preferably re-enforced by washers 19 and 20, respectively, preferably formed from fabric. In this instance, the apices of the diaphragms are clamped to each other between metallic washers 21 and 22 positioned upon the sleeve or bushing 17, the sleeve or bushing 17 being provided with an outwardly extending flange 23 and a nut 24 for this purpose. 75

One end of the sleeve or bushing 17 is preferably slotted longitudinally, and is preferably screw-threaded, as at 25, to receive a nut 26 having an extension 27. The extension 27 has a conical inner surface engageable with 80 a similar surface provided upon the slotted end of the sleeve or bushing 17. The construction is such that the nut 26 may be manipulated to clamp the slotted end of the sleeve or bushing 17 against a rod 30 to rigidly secure the rod to the sleeve. One end of the rod 30 is rigidly secured to a relatively flexible and resilient arm 32 which has one of its ends rigidly secured to a bracket member 85 33 by a screw 34, the other end of the arm 32 being secured to one end of a pin 35 which has its other end secured to an armature 36 forming part of a reproducing unit indicated generally by reference character 37. It will be noted that the rod 30 is connected to the arm 32 intermediate the ends of the arm and it will be readily understood that vibration of the armature 36 will be transmitted to the diaphragms 14 and 15 through the pin 35, 90 the arm 32 and the rod 30. 95

As best shown in Figs. 1, 2 and 3, the bracket member 33 comprises a central disc portion 40 having integral arms 41, 42 and 43, the arms 42 and 43 being secured to one of the bars 12 and one of the bars 11, respectively, by screws 45, or the equivalent. At its outer end, the arm 41 is provided with an aperture 48 to accommodate a rod 50 which has one of its ends rigidly secured to a cup-shaped member 51 fastened to the uppermost bar 11. It will be noted that the cup-shaped member 51 is seated in a recess 53 formed in the bar 11 and that a compression spring 54 is disposed around the rod 50 and is interposed between the cup-shaped member 51 and the arm 48. The compression spring 54 tends to displace the bracket member 33 in a direction away from the diaphragms 14 and 15, but such displacement is limited by a knurled nut 56 screw-threaded upon the rod 50.

Secured to the bracket member 33 is a permanent magnet 60, the legs of the magnet being apertured to receive bolts 61 and 62 which co-operate with nuts 63 and 64, respectively, to rigidly secure the magnet in place upon the bracket 33. The magnet is preferably provided with pole pieces 65 and 66 having U-shaped ends which terminate adjacent the ends of the armature 36 (see Fig. 4). Disposed within the U-shaped ends of the pole pieces 65 and 66 is a winding 68 carried by a sleeve 70 which is formed from non-magnetic material. The armature 36 is resiliently mounted within the sleeve 70 by any suitable means, such as, for instance, a relatively thin piece of sheet metal 72. As is well known to those skilled in the art when the winding 68 is subjected to telephonic currents, the armature 36 vibrates and this vibration is transmitted to the diaphragms 14 and 15 which translate them into sound.

The means for operatively connecting the winding 68 to a source of telephonic current, preferably comprises conductors 75 and 76 connected to the terminals of the winding. The outer ends of the conductors 75 and 76 are connected to terminals 78 and 79, respectively, carried by a bar 80 formed of electrical insulation. The bar 80 is apertured to receive a bolt 82 screw-threaded through the bracket member 33 and nuts 83 screw-threaded upon the bolt secure the bar 80 thereto. Suitable conductors, as indicated at 87 and 88, may be provided to connect with the terminals 78 and 79 to the output circuit of a radio-receiving set, or the equivalent.

Obviously, the nut 26 may be manipulated to clamp the slotted end of the sleeve 17 in any desired position upon the rod 30 so that the diaphragms 14 and 15 will be correctly positioned with respect to the arm 32 and there will be no tendency to distort the sound waves propagated by the diaphragm. It is also apparent that the nut 56 may be manipulated to displace the bracket member 33

against the action of the spring 54 or in the direction of the action of the spring 54 to properly position the winding 68 and sleeve 70 with respect to the armature 36 so that when the armature 36 is not energized, it will occupy a predetermined position within the sleeve.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as possible, in view of the prior art.

What I claim as new is:

A sound reproducing device comprising a frame, a diaphragm extending across said frame, a second frame mounted on the first mentioned frame, a second diaphragm mounted on said second frame, a bracket having one of its ends secured to said second frame, a bolt secured to said second frame and extending through the other end of said bracket, a spring urging said bracket in one direction, a nut screw-threaded on said bolt and adapted to displace said bracket against the action of said spring, a sound reproducing unit mounted on said bracket intermediate its ends, said sound reproducing unit having an armature and means including a flexible member for operatively connecting said armature to said diaphragms.

In testimony whereof, I have hereunto set my hand this 17th day of May, 1929.

PAUL G. ANDRES.
